UNITED STATES PATENT OFFICE

ALFRED C. SCHMOHL, OF BEAVER FALLS, PENNSYLVANIA, ASSIGNOR TO PRESSED STEEL CAR COMPANY, OF PITTSBURGH, PENNSYLVANIA, A CORPORATION OF NEW JERSEY

CAR CONSTRUCTION

Application filed July 20, 1929. Serial No. 379,724.

My invention relates to cars, and particularly to the type known as cane cars, which have open ends and little or no bracing at the sides.

5 An object of my invention is to provide a brace for the corner post of car which will hold that member rigid.

Another object of my invention is to provide a corner post and brace for a car in which 10 the post and brace for a portion of the length of the post, form a box like structure to strengthen the connection between the post and car underframe.

Referring now to the drawings, Fig. 1 is a 15 portion of the end of the car embodying the post and brace construction of my invention; Fig. 2 is an enlarged detail plan view of the brace; Fig. 3 is an end elevation of the brace; Fig. 4 is a section taken along the line 4—4 20 of Fig. 1.

Referring now to the drawings where like reference characters refer to like parts, reference character 1 indicates a car having end, 25 sills 2, side sills 3, and corner posts 4. Only a portion of the end of the car has been shown but it is to be understood that the car is symmetrical about the center line 1—1 of Fig. 1. In the preferred embodiment of the invention, the tops of the corner posts are 30 secured together by a tie member 5 and tie members 7 spaced between the tie 5 and the end sill. Spaced transversely of the car are intermediate posts 6 secured to the end sill and tie members 5 and 7. A brace member 8 35 is attached to the lower portion of the corner post and the adjacent sill member. The brace member 8 is made to extend beyond each side of the sill member and engage with corner post to provide greater rigidity in the post.

40 The post 4 is preferably made Z-shaped, having a portion 9 secured to the end sill and a portion 10 spaced from the end sill and parallel with the portion 9. The brace member 8 is also preferably made Z-shaped, having the portion 11 secured to the end sill and a portion 12 spaced from the end sill and extending parallel thereto beyond each side and the portion 12 is secured by means of rivets or other fastening members to the portion 10 of 45 the corner post. This construction provides

greater strength to prevent the bending of the post in a direction longitudinal of the car and also provides a greater resistance to bending transversely of the car.

The corner post and brace have been shown 55 in the drawings as being both secured to the end sill in order to give a greater capacity to the car for a given length of underframe but it is to be understood that either one or the other may be placed on the side of the car 60 if desired.

Having thus described my invention, what I claim as new and desire to secure by Letters Patent is:

1. In a car construction an end sill, side sill, 65 and corner post connected together, a brace member connecting said corner post and end sill, said brace having a portion thereof spaced from said end sill and extending above and below said sill to engage with said corner 70 post.

2. In a car construction comprising an end sill, side sill and corner post connected together, said corner post having a portion spaced from said end sill, a brace secured 75 to said end sill and having a portion spaced therefrom and a connection between said spaced portions of the post and brace.

3. In a car construction comprising an end sill, side sill and corner post connected together, said corner post extending on each side of said end sill, a Z-shaped brace member secured to one of said sills and to said corner post.

4. In a car construction comprising an end sill, side sill and corner post all connected together, a brace member secured to one of said sill members, said brace member and post having portions spaced from said sill members to which they are secured and a connection between said spaced portions.

ALFRED C. SCHMOHL.
